DEAERATING AND DEOILING MACHINE

Charles Gilbert Hawley, Chicago, Ill., assignor to
Centrifix Corporation, Cleveland, Ohio, a cor-
poration of Ohio

Continuation of application Serial No. 124,681,
July 24, 1926. This application April 5, 1932,
Serial No. 603,417. Renewed November 3, 1933

5 Claims. (Cl. 210—61)

This invention relates to the important and little-developed art of removing oils and gases from liquids that should be freed from such foreign substances. Such is the object of the present invention.

As will presently appear the machine embodying this invention is of a centrifugal type in which the stream of liquid under treatment is set into a state of rotation which increases the travel of the liquid and affords ample time for the separation of the lighter substances. Further and importantly, the entrance of the liquid to the machine is accompanied by the fine sub-division of the liquid stream and disturbances which effect the combing out or liberation of even minute particles and globules of gas or oil that are very closely or firmly occluded in the liquid. Further and of utmost practical value, the whirling action of the liquid, which takes place within the machine as above mentioned, is suppressed in the region in which the lighter substances accumulate following their separation from the liquid. Without such protection, the vortexial action of the liquid within the machine would inevitably result in the extraction of the separated substances and the discharge thereof from the machine along with the stream of liquid.

The invention also consists in novel combinations of parts and in details of construction comprising such machine, and whereby the foregoing process may be reliably conducted; all as hereinafter described and particularly pointed out in the claims.

The invention will be readily understood on reference to the drawing that forms part of this specification; and in which, Fig. 1 is a vertical section of a machine embodying the invention and whereby the novel process may be carried out; Fig. 2 is a horizontal section thereof on line 2—2 of Fig. 1; Fig. 3 is a horizontal section on the line 3—3 of Fig. 1.

The machine in its best form comprises a vertical casing preferably composed of the large dome portion 2 and the smaller bottom portion 3. The dome portion is a closed vessel, and is provided with the valved and normally closed top outlet 4 for the gases, and preferably with the lower, side outlet 5 for the discharge of the oil or other liquid impurities. The outlet 5 in practice is also valved and normally closed. Obviously, in operations of large size the outlets 4 and 5 may be continuously open, but a better understanding of the invention will be gained by first regarding them as normally closed and only intermittently opened to discharge the col-

lected substances. The bottom member 3 contains the flow-balancing opening 6, the underlying chamber 7 and the outlet connection 8. The stand-pipe 9 rises from the central portion 7 and passing through the chamber 7 is expanded within the dome; to form the head 10. The liquid inlet pipe 12 enters the lower end of the stand-pipe 9. The liquid outlet pipe 13 leads away from the connection 8. Upon the removal of the bottom bolts 11, the dome 2 may be removed from the parts 3 to 10 forming the bottom of the machine.

It should at once be understood that the pipes 12 and 13 rise to heights above the dome, or are used under sufficient pressure to keep the dome filled with liquid at least to the height of the side outlet pipe 5. Further, it is to be understood that the gas outlet 4 is opened whenever the liquid level, L, is forced below the side outlet by the accumulation of gas in the top of the dome. In practice, the dome is equipped with a gage (not shown), either serving to automatically release the accumulating gas or to make the liquid level, L, visible so that the outlet 4 may be manually opened when required. Gages of such kinds are too well known to require illustration herein.

On entering the head 10 the burdened liquid, that is, the liquid which is burdened or contaminated by impurities of either solid, gaseous or liquid form and of less specific gravity encounters the centrifugal tuyère 14, which has many inwardly directed narrow slit-like tangential tuyères 14'. The tuyère is provided with an imperforate bottom 14'', so that all of the liquid from the space 10' must pass through the tangential tuyères in order to reach the exterior of the head 10, and find a passage leading downward to the outlet. Obviously the liquid takes on a rapid whirling motion within the tuyère. Conveniently, the barrel of the tuyère is provided with a top flange 15 whereby it is attached to the top of the head 10. The fine sub-division of the liquid in the tuyères of the member 14, and the impingement of the liquid against the many edges of the tuyère forming blades thereof, serve to disturb and free the particles or globules of gas and oil carried by the liquid; and the whirling of the liquid within the tuyère 14 accomplishes an excellent centrifugal separation of the substances and in such state they are expelled upwardly through the open upper end of the tuyère 14. Several rotations, of any given part of the liquid, take place in the tuyère and thus ample time is allowed for both the centrifugal and the gravity separation and agglomeration of the minute globules, so that globules and bubbles of consid-

erable size equally rise from the tuyère. On entering the body of the dome, these rise rapidly to the top thereof while the purified liquid descends at the sides of the head 10 and through the opening 6, thus reaching the outlets 8 and 13. The outlet 8 is most convenient when designed as here shown, and the tendency of the side outlet to draw more vigorously from one side of the dome is corrected by making the hole 6 properly eccentric to the stand-pipe 9 and space 7, (see Fig. 1).

Were the whirling liquid allowed to escape freely from the tuyère, the whole body of liquid in the dome would be set into rapid rotation and a downward drawing central vortex, starting at the level, L, would be set up and necessarily in direct connection with the outlet. Any such central vortex would have the effect of emptying the top of the dome and the intended purpose of the machine, at least in large measure, would be defeated.

For the avoidance of so vital a defect, I employ means which prevent the communication of the whirling motion in the tuyère to the liquid in the top of the dome and which therefore prevent the initiation of the objectionable vortex at the liquid surface or level. The means referred to possess the advantages of extreme simplicity and durability comprising only the barrel 16 and the vertical spaced blades or baffles 17 therein. The device is called a cellular barrel, interposed between the source of whirling motion and the level at which the lighter or floatable substances are "disengaged" from the heavier liquid.

Most conveniently the barrel 16 is a mere upward extension of the stationary tuyère, being secured to the head 10 by the same flange 15. It should be apparent that the cellular barrel and the dome need not be circular but may be of any desired shape in cross section.

This application is a continuation of applicant's earlier filed application, S. N. 124,681 filed July 24, 1926.

Having thus described my invention, I claim as new and desire to secure by Letters-Patent:

1. A machine for separating lighter floatable substances from liquids of greater weight, comprising a casing having a liquid outlet at its bottom, in combination with a liquid inlet passage rising within the lower part of said casing, a tangentially bladed tuyère fixed within and forming part of said passage, and, a cellular duct positioned below the liquid level in said casing and forming the outlet for said tuyère and passage.

2. A machine for separating lighter floatable

substances from liquids of greater weight, comprising a casing having a liquid outlet at its bottom and provided with means for discharging the separated substances from its top, in combination with a liquid inlet passage rising within the lower part of said casing, a whirl-promoting tuyère positioned in and forming part of said passage, and, a longitudinally subdivided vertical duct positioned below the liquid level of said casing and forming the outlet for said whirl-promoting tuyère and passage.

3. A machine for separating lighter floatable substances from liquids of greater weight, comprising a casing having a liquid outlet in its bottom and provided with means for discharging the separated substances from its top, in combination with a liquid inlet passage opening upward within the intermediate part of said casing, an angularly bladed whirl-promoting tuyère interposed in and forming part of said passage, and, whirl suppressing means positioned in the upper part of said passage.

4. A liquid purifier comprising a casing adapted to contain a stand of liquid and having its upper part open for the discharge of impurities from the top thereof, said casing having a purified liquid outlet in its lower part, in combination with a liquid inlet passage of smaller diameter than and opening vertically within the intermediate part of said casing, means incorporated with the lower part of said inlet passage and adapted to cause the entering liquid to rotate vortically therein, and, means within the upper part of said inlet passage and adapted to terminate such whirling movement of the liquid and direct it upward toward the top of said stand of liquid within the casing.

5. A liquid purifier comprising a casing adapted to contain a stand of liquid and having its upper part open for the discharge of impurities from the top thereof, said casing having a purified liquid outlet in its lower part, in combination with a liquid inlet passage of smaller diameter than and opening vertically within the intermediate part of said casing, a tangentially slotted tuyère positioned within the lower part of said inlet passage and adapted to cause the entering liquid to rotate vortically therein, and, an opposing bladed structure positioned within the upper part of said inlet passage and adapted to terminate such whirling movement of the liquid and direct it upward toward the top of said stand of liquid within the casing.
